UNITED STATES PATENT OFFICE.

WILLIAM H. DEGGES, OF WASHINGTON, DISTRICT OF COLUMBIA.

IMPROVEMENT IN SHIP-BUILDING.

Specification forming part of Letters Patent No. 38,294, dated April 28, 1863.

To all whom it may concern:

Be it known that I, WILLIAM H. DEGGES, of the city of Washington, in the District of Columbia, have invented certain new and useful Improvements in the Construction of Vessels; and I do hereby declare the following to be a full, clear, and exact description thereof, reference being had to the accompanying drawings and to the letters and marks thereon.

The drawings, forming part of this specification, show, by Figure 1 a bottom view of a vessel constructed in accordance with my invention, and by Fig. 4 a transverse section of the same, the section being on a line drawn just behind the engine. Figs. 2 and 3 are views of the propeller intended to be used in connection with the vessel.

In each of these drawings where like parts are shown, like letters are used to indicate the parts.

The ends *a* and *b* of this vessel are both sharp, or are like bows, and have rudders *c* and *d*, so that the vessel may be driven in either direction as may be desired. The deck *e* is arched. It will be noticed that instead of the usual continuous curved-line sides of vessels from the deck to the keel, the sides *f* of this vessel have recesses *g*, in which are placed the propellers *h*. That part of the sides above the propeller-space may have a keel, *i*, as shown, or may be of a somewhat different line from that shown. The line of the bilge *j* may also vary from what is shown, and although the recesses will extend through the entire length of the vessel the propellers may occupy but a portion thereof. The propellers may be driven by independent engines by toothed wheels *k* and *l* or by cranks, the means for operating them that pass through the sides of the vessel being suitably protected by watertight casings.

The recesses *g* occur from the peculiar construction of this vessel, and while they form a

space for the propeller and water-way, they add to the buoyancy, the capacity, and the strength of the vessel. They also allow of a vessel of any specified tonnage being made for shallow water, as the breadth of beam will be greater than in ordinary vessels. In ocean vessels greater steadiness will exist and an easier riding on the wave with an increased degree of speed. It will readily be seen, too, that the iron-clad or "monitor" class of vessels may be constructed on this plan, as the propeller will be fully sheltered, the engine readily protected, and the vessel be strong and staunch, the arched deck, in connection with the recessed form of the sides, adding greatly to the strength of the vessel. Vessels of any and every size may be constructed on this plan either of wood and timber, or of metal, either alone or in connection with wood. If made of wood the timbers for the ribs can be hewn, or can be steamed and bent to the form necessary to pass from the keel or keelson to the deck; and if made of cast-metal or of wrought-metal the timbers can readily be made to the required form. Vessels made on this plan can effectually be used as "rams," and the vessel can be sunk to the edge of the deck, leaving the base on which the turret moves on the arch of the deck when the turret is five feet above the water.

What I claim as my invention, and desire to secure by Letters Patent, as an improvement in the construction of vessels, is—

So forming the sides thereof as that recesses continuous throughout the length of the vessel will exist therein, as and for the purposes herein set forth.

This specification signed this 1st day of April, 1863.

W. H. DEGGES.
